(57) **CLAIM**

The ornamental design for an infant carrier, as shown and described.

DESCRIPTION

FIG. 1 is a perspective view, taken from the front, right side, of the infant carrier according to my design;

FIG. 2 is a front view thereof;

FIG. 3 is rear view thereof;

FIG. 4 is a left side view thereof, the right side view being a mirror image thereof;

FIG. 5 is a top view thereof; and,

FIG. 6 is a bottom view thereof.

The broken lines for various components illustrated in FIGS. 1–2 and 4–6 are for illustrative purposes only and form no part of the claimed design.

1 Claim, 6 Drawing Sheets

FIG. 1

FIG. 2

FIG. 3

FIG. 4

FIG. 5

FIG. 6
